APPARATUS FOR FINNING PIPE

Robert F. Moyer, Providence, R. I., assignor, by mesne assignments, to National-U. S. Radiator Corporation, a corporation of Maryland

Application August 22, 1951, Serial No. 243,054

10 Claims. (Cl. 29—202)

The present invention relates to apparatus for finning pipe. 15

In accordance with the present invention pipe is provided with radially extending flat heat dissipating fins in which each of the fins is provided with a sleeve terminating in a reduced neck portion. The fins are assembled one at a time over the pipe and each succeeding fin is pressed home with a predetermined pressure so as to draw the relatively larger sleeve portion of each fin over the reduced neck portion of the sleeve of the preceding fin. In this way improved heat conducting transfer is provided between the enlarged sleeve portion of each fin and the reduced neck portion of the adjacent sleeve, as well as between the reduced neck portion of each fin and the pipe.

It is an object of the present invention to provide fins on pipes.

It is a further object of the present invention to provide apparatus operable automatically to advance a succession of sleeved fins over a pipe and to seat each fin upon the sleeve portion of the preceding fin at a predetermined substantially constant pressure.

It is a further object of the present invention to provide fully automatic mechanism for finning pipe comprising means for supporting the pipe from one end, a plurality of carriers movable longitudinally of the pipe, means for supplying fins to the carriers as they advance toward the pipe, and means on the carriers for supporting sleeved fins for applying each fin successively in fully seated relationship with respect to the preceding fin.

Other objects and features of the invention will become apparent as the description proceeds, especially when taken in conjunction with the accompanying drawings, wherein:

Figure 1 is a fragmentary longitudinal section through a pipe provided with fins as accomplished by the apparatus described herein.

Figure 2 is a simplified perspective view showing the general relationship between parts of the apparatus.

Figure 3 is a plan view of the sub-assembly comprising the carrier chain arm and the carrier chain slide bracket.

Figure 4 is a section on the line 4—4, Figure 3.

Figure 5 is a front elevation of the structure shown in Figure 3.

Figure 6 is a plan view similar to Figure 3 showing the parts in position to release a sleeved fin.

Figure 7 is a plan view of camming mechanism employed in resetting the fin supporting levers.

Figure 8 is a side elevational view of the camming mechanism shown in Figure 7.

Figure 9 is a rear elevation of the mechanism at the loading station showing one of the sleeved fin carriers in position thereat.

Figure 10 is a side elevation of the construction shown in Figure 9.

Referring now to the drawings the apparatus forming the subject matter of the present invention is adapted to provide heat conducting and radiating fins on a pipe. In

Figure 1 there is illustrated at 10 a section of pipe provided with a plurality of sleeved fins 12, each fin comprising a flat radially extending fin portion 14, an enlarged tubular sleeve portion 16, and a reduced neck portion 18. 5 In assembling the fins 12 on the pipe each fin is successively seated in the illustrated relationship so that its sleeve portion 16 is drawn over the reduced neck portion 18 of the preceding fin in tightly fitting relationship.

One of the advantages of the finned pipe when constructed in accordance with the present invention is that in drawing each of the fins over the pipe it is possible that the reduced neck portion may be somewhat expanded due to variations in diameter of commercial piping longitudinally thereof. However, even though the reduced neck portion 18 of a particular fin may have been drawn over an enlarged portion of the pipe 10 prior to reaching its final position, it will nevertheless be pressed back into firm heat conducting relationship with the pipe as the enlarged sleeve portion 16 of the next succeeding fin is drawn thereover. It will be appreciated that the enlarged sleeve portion 16 is of substantially larger diameter than the outside diameter of the pipe so that in no case will this portion of the fin be expanded as it is drawn along the pipe.

25 At the juncture between the sleeve portion 16 and the reduced neck portion 18 there is provided a shoulder 20 which serves as a seat limiting movement of the next succeeding fin onto the pipe. This in turn insures uniform spacing between finned portions 14 and also serves as 30 a positive stop for the advance of each fin, which in the operation of the machine has the effect of first building up the pressure with which the fin is applied and thereafter releasing the fin holding means.

In order to carry out the assembly of fins on a pipe in 35 a rapid and efficient manner, mechanism which is fully automatic in its operation and which is adapted to assemble fins at a high production rate, is described herein.

Referring now to Figure 2 there is a simplified illustration of the mechanism used primarily for the purpose of 40 locating the component parts of the apparatus with respect to each other. As seen in this figure the apparatus comprises a frame including a bed 22 which is herein disposed of substantial length and arranged horizontally. At opposite ends of the frame are sprockets 24, only one 45 being visible in Figure 2. Over the sprockets 24 is a conveyor in the form of an endless chain 26 provided with a plurality of spaced carriers indicated generally at 28. A support is provided for the pipe, the support being illustrated at 30, and is adapted to support the pipe 10 in 50 position above and parallel to the longitudinal extent of the bed 22. The support 30 supports the pipe from one end and leaves its other end unsupported for entering into the opening through the sleeved fins as they are advanced serially by the carriers 28.

55 Extending along the bed 22 at opposite sides thereof are pairs of longitudinally extending guides or ways 32. The bed 22 includes inwardly extending flanges 34 which cooperate with the ways 32 so as to provide enclosed trackways for cooperation with carrier supporting structure subsequently to be described.

At the front of the machine there is provided a loading station indicated generally by the numeral 36 which includes a vertically extending chute 38 in which a plurality of sleeved fins 12 are provided.

60 In general the operation of the apparatus involves continuous advance of the chain 26 so that its upper run moves from right to left as seen in Figure 2. The plurality of carriers is thus caused to pass the loading station at which point each carrier picks up a single sleeved fin. The carrier then advances longitudinally of the pipe in position such that the fin is sleeved over the pipe and is pressed into assembled relationship with

respect to the previously assembled fin. As a predetermined pressure is built up, the fin is released from the carrier and the carrier advances around the sprocket at the left or the rear of the machine and returns to the loading station to pick up a second fin.

Referring now to Figures 3-7 the carrier 28 comprises a carrier chain arm 40 constituting a carriage which is rigidly secured to the chain and advances at a uniform rate therewith. Associated with the carrier chain arm 40 is a carrier chain slide bracket 42. The carrier chain slide bracket is relatively movable with respect to the carrier chain arm 40 and is guided for such movement by guide pins 44 extending through openings in the carrier chain arm 40 and through corresponding openings in shoulder bushings 46. Thus the carrier chain slide bracket is movable with respect to the carrier chain arm in a direction parallel to and opposite the direction of advance of the carrier.

Resilient means normally holding the slide bracket 42 in abutment against the carrier chain arm 40 are provided and as illustrated, take the form of headed bolts 48 extending through openings 49 in portions of the carrier chain slide bracket and are threaded to occupy tapped openings in portions of the carrier chain arm 40. The headed bolts 48 are provided with compression springs 50 which are compressed as the carrier chain slide bracket moves to the right relative to the carrier chain arm, as seen in Figures 3, 4, and 6.

The position of the parts when the carrier chain slide bracket 42 has moved to the right relative to the carrier chain arm 40 is illustrated in Figure 6.

The carrier chain slide bracket 42 has portions 52 at the end thereof which extend upwardly above the plane of the arm 40 and include forwardly extending portions 54 which overlie the carrier chain arm 40. The forwardly extending portions 54 of the slide bracket are each provided with an upwardly extending stripper bolt 56 and pivoted to each of these bolts is a fin seating lever 58. The bolts 56 are provided with heads 60 and compression springs 62 are provided intermediate the heads 60 and the levers 58 to normally retain levers 58 in position against washers 63 located above the upper surface of the forwardly extending portions 54 of the slide bracket 42.

Each of the levers 58 includes an arcuate fin carrying portion 64 as best illustrated in Figure 5. In addition, each of the levers 58 carries small leaf springs 66 for a purpose which will presently appear. The arcuate portions 64 are dimensioned so that they surround the sleeve portion of a sleeved fin and engage the radially extending flange portion thereof to a point substantially at the juncture between the fin portion and the sleeve portion thereof. The leaf springs 66 press against the sleeve portion of the fin and insure retention of the fin in the arcuate portions 64 of the levers 58 as the fins are carried from the loading station into assembled relation on the pipe.

In order to retain the levers 58 against swinging movement to release the fins until a predetermined and relatively large pressure has been applied to the assembled fin, the levers 58 are provided with elongated open-ended slots 68 having at least one side 70 thereof parallel to the direction of motion of the carrier and spaced rearwardly from the axis of the bolts 56.

The carrier chain arm 40 adjacent each end thereof includes an upwardly extending portion 72, the portion 72 being spaced apart so as to be received between the upwardly and forwardly extending portions 52 and 54 of the carrier chain slide bracket, as best illustrated in Figure 5. Provided on each of the upwardly extending portions 72 of the carrier chain arm are pins 74 carrying rollers 76 adapted to enter the slots 68 and to engage the parallel surfaces 70 thereof. With the parts in the relationship illustrated in Figure 3 it will be ob-

served that the surfaces 70 of the slots 68 engage the rollers 76 in such a manner that rearward swinging movement of the levers 58 is effectively prevented. Moreover, this relationship is preserved as the carrier chain slide bracket 42 yields rearwardly from the direction of advance of the carrier chain arm 40 until the axes of the pins 74 pass the ends of the surfaces 70. At this time, since the yielding movement of the carrier chain slide bracket 42 was the result of pressure applied to the arcuate portions 64 of the levers, the levers will snap rearwardly to the position illustrated in Figure 6, this rearward swinging motion of the levers 58 being limited by engagement with buffers 78 provided on the carrier chain slide bracket 42.

The ends of the carrier chain arm 40 are provided with enlarged plates 80 to which are secured roller supports 82 carrying sets of rollers 84 spaced at 120-degree angles with respect to each other and engageable with surfaces of guide plates 86 carried by the guides 32 and the overhanging flange 34. Thus, the carrier chain arm 40 is advanced continuously by the chain 26 in accurately supported relation determined by the rollers 84 and the surfaces of the guide plates 86.

As the carrier 28 advances a sleeved fin onto the pipe, the rollers 76 positively lock the levers 58 against rearward swinging movement until substantial resistance to forward movement of the fin is encountered. Thus, the fin is seated with its sleeve portion drawn firmly over the reduced neck portion of the preceding fin by a combination of impact and continuously applied pressure. As the resistance to forward movement of the fin increases, forward movement of the slide bracket 42 is retarded until the levers 58 carried thereby reach a position in which the rollers 76 are at the open ends of the slot 68. At this time the pressure applied by the fins to the levers 58 establishes a relatively large force tending to rotate the levers to the right as seen in Figure 3, and this releasing movement of the levers takes place rapidly when the levers are released by relative withdrawal of the rollers 76 from the slots. This rearward releasing swinging movement of the levers 58 of course releases the carrier chain slide bracket 42 for return movement into abutting relation against the rear surface of the carrier chain arm 40 under the influence of the springs 50 and this takes place while the levers 58 remain in the retracted or released position illustrated in Figure 6. By this operation the fin carried by the carrier has been assembled over the pipe and drawn into properly nested relation with the preceding fin and thereupon released.

The carrier continues its movement past the assembled fins and around the sprocket at the rear end of the frame and thence forwardly at the underside thereof. It is of course necessary to reset levers 58 in their original carrying position illustrated in Figure 3. The mechanism for accomplishing this purpose is best illustrated in Figures 7 and 8.

As seen in these figures the levers 58 engage a gradually inclined camming surface 90 with the result that the levers are moved axially of the pivot pins 56 against the compression of springs 62 until the levers are displaced beyond the ends of the rollers 76. At this time surfaces 92 of the levers engage cams 94 which causes the levers to swing to the position illustrated at the right in Figure 7 at which time the slots 68 in the levers are located in registry with and beyond the ends of the rollers 76. Thereupon the levers move beyond the end of a straight continuation 96 of the camming surface 90 and are pressed into assembled relation with the rollers 76 by the action of the compression springs 62. Thus, during the return motion the levers 58 are first moved outwardly beyond the roller 76, thereafter swung into registration with the roller 76, and finally released to be returned by the compression spring 62 to the reset position.

The mechanism for applying a fin to each pair of levers 58 as it passes the loading station 36, is best illustrated in Figures 9 and 10. As seen in these figures, a vertical chute 38 contains a plurality of sleeved fins 12 which are adapted to descend by gravity.

The loading station comprises generally an arch 100 spanning the path of advance of the carriers 28 and includes means for providing a sleeved fin 12 in position to be picked up by each carrier and for thereafter advancing a second sleeved fin into position to be picked up by the following carrier. The supply of finned carriers in the chute 38 is retained in position in the chute and is released one at a time by a rocker arm 102 pivoted as indicated at 104 to a bracket 106. The rocker arm 102 includes an upper shoe 108 and a lower shoe 110 and is adapted to be rocked back and forth so as to release the fin carried by the upper shoe and to let it drop by gravity into engagement with the lower shoe, and upon reverse movement to release the fin carried by the lower shoe and to move the upper shoe into position to retain the supply of fins thereabove in position.

The fin in the position indicated in dotted lines at 12A is in position to be picked up by the arcuate portions 64 of the levers 58. The fin in this position has dropped down the chute 38 and is held in this position by a guide portion of the chute to the right thereof as seen in Figure 10, and by a lever 112 having an arm 114 extending across and engaging the fin at diametrically opposite points. The purpose of the lever 112 and the arm 114 is to support the fin and to insure that it is properly located in the advancing arcuate portions 64 of the lever before it is released. For this purpose the lever 114 is keyed or otherwise secured to a shaft 116 supported in brackets 118 on the arch 100. A coil spring is contained in a housing 120 carried by the arch 100 and is connected to the shaft 116 through a coupling 122. The spring in the housing 120 thus biases the lever 112 and the arm 114 with a predetermined force resisting displacement of the fin by the advancing arcuate portions 64 of the levers 58 until the fin is firmly seated therein.

It is necessary to provide means for quickly moving the arm 114 away from the fin to prevent it being dragged upwardly along the forward surface of the fin as the fin ultimately advances. The mechanism for accomplishing this purpose comprises a lever 124 keyed or otherwise secured to the shaft 116 and in position to be engaged by a camming element 126 mounted on each of the carriers 28. The arrangement is such that as the forward edge 128 of the camming element 126 engages the lever 124, the lever is rocked in a clockwise direction thus swinging the arm 114 rapidly away from the advancing fin. The purpose of the inclined portion 130 of the camming element is to permit a gradual return of the lever 124 to the full line position shown in Figure 10.

In order to release a second fin for movement by gravity into position to be engaged by the next carrier, rotation of the shaft 116 resulting from actuation of the lever 124 is utilized to rock the rocker arm 102. This is accomplished by providing a lever 132 which is keyed or otherwise secured to a shaft 134, which in turn carries the rocker arm 102. The lever 132 is engaged adjacent its lower end by a forwardly extending portion of a lever 136, the forwardly extending portion thereof extending through beneath the arch, as best seen in Figure 10. As the shaft 116 is rotated by the lever 124, the lever 136 is of course rotated therewith and permits clockwise rotation of the lever 132. Clockwise rotation of the lever 132 is induced by a tension spring 138 which connects the arch with a lever 140, this lever

also being keyed or otherwise secured to the shaft 134. An adjustable abutment 142 is carried by the lever 140 and predetermines the amount of rocking which can take place from the position shown in Figure 10. This amount of rocking is determined by engagement between the end of the abutment screw 142 and the adjacent surface of the arch 100, and this in turn is selected such that it permits release of the fin engaged by the upper shoe 108 and moves the lower shoe 110 in position to engage a fin.

It will be observed that the arcuate portions 64 of the levers 58 are spaced apart to pass on opposite sides of a supporting bar 144. Moreover, in general, the carrier 28 comprises upstanding structure at the sides thereof and the loading station 36 includes structure depending from the arch 100 to occupy the space between the upstanding structure at the ends of the carrier 28.

Briefly reviewed, the operation comprises automatically placing a fin in position to be picked up by the arcuate portions 64 of the levers 58 and retaining the fin in position by substantial spring pressure to cause the fin to seat firmly in the opening defined by the arcuate portions 64. Thereafter, the carrier advances and assembles the fin with its sleeve on the reduced neck portion 25 of the preceding fin. This assembly is the result of combined impact and pressure, and when the pressure is sufficient the rollers 76 are withdrawn from the slots 68 to permit rearward swinging motion of the levers 58, thus releasing the fin and permitting the carrier to move 30 on past the assembled fins. The levers remain in released position until they are cammed, first axially of their supporting pivot bolts and then about such axis until the slots 68 therein are again in registry with the rollers 76. At this time the lever arms ride off the cams which 35 have effected movement axially of the pivot bolts and the levers drop down into engagement with the rollers 76. The machine is capable of producing finned pipes at a high rate of production and is particularly characterized in that it seats each fin with a predetermined pressure 40 upon the appropriate parts of the preceding fin.

By employment of the present apparatus it is possible to provide heat transfer fins on commercial piping which may have substantial variation in outside diameter. This is accomplished in a manner which insures good heat transfer relationship between the sleeve and neck portions 45 of the fins and the pipe.

One of the advantages which results from operation of the present machine is that the tubular sleeve of each fin is drawn over the reduced neck portion of the preceding fin by forces applied to the fin portion of the sleeved 50 fin. Thus, the sleeve portion of the fin is drawn under tension over the reduced neck portion rather than being forced thereover by compression. This offers substantial advantages and contributes to the uniformity and high efficiency of the finished product.

The drawings and the foregoing specification constitute a description of the improved apparatus for finning pipe in such full, clear, concise and exact terms as to enable any person skilled in the art to practice the invention, the 60 scope of which is indicated by the appended claims.

What I claim as my invention is:

- Apparatus for assembling sleeved fins on pipe in which the sleeves of the fins are partially telescoped by the application of substantially equal forces to each fin 65 as it is telescoped over the sleeve of the preceding fin which comprises: means for supporting a pipe from one end only thereof, a carriage movable longitudinally of the pipe from the unsupported end toward its supported end, means for advancing said carriage continuously at a uniform speed, a fin seating member carried by said carriage shaped to engage a fin to be assembled on the pipe, guide means on said carriage mounting said fin seating member for movement relative to said carriage parallel to the line 70 of advance of said carriage, spring means opposing move-

ment of said fin seating member rearwardly of the direction of advance of said carriage, a pivot support for said fin seating member having its axis perpendicular to the path of advance of said carriage, and lock means for said fin seating member effective to lock said fin seating member against swinging movement about the axis of its pivot support, said lock means being releasable upon predetermined movement of said fin seating member relative to said carriage.

2. Apparatus as defined in claim 1 in which said lock means comprises relatively slidable abutments on said carriage and fin seating member, said abutments having abutment surfaces which are disengageable upon predetermined rearward displacement of said fin seating member relative to said carriage.

3. Apparatus as defined in claim 1 in which said lock means comprises an open ended slot and pin connection between said carriage and said fin seating member.

4. Apparatus as defined in claim 1 in which said lock means comprises a slot in said fin seating member having an open end toward the direction of advance of said carriage, and a pin on said carriage movable out of the open end of said slot as said fin seating member is displaced oppositely to the direction of advance of said carriage relative to said carriage.

5. Apparatus for assembling sleeved fins on pipe in which the sleeves of the fins are partially telescoped by the application of substantially equal forces to each fin as it is telescoped over the sleeve of the preceding fin which comprises: means for supporting a pipe from one end only thereof, a carriage movable longitudinally of the pipe from the unsupported end toward its supported end, means for advancing said carriage continuously at a uniform speed, a support movable relative to said carriage in a direction parallel to the line of advance of said carriage, resilient means opposing rearward yielding of said support, a fin seating lever on said support, a pivot element on said support having its axis perpendicular to the line of advance of said carriage, said lever being mounted on said element for swinging movement and for displacement axially thereof, spring means urging said lever toward said support, said lever and carriage having cooperating abutment means preventing swinging of said lever on said support until predetermined rearward displacement of said support relative to said carriage, and cam means operable during advance of said carriage after a fin seating operation to displace said lever axially on said pivot element to separate said abutment means and to thereafter swing said lever to a position in which said abutment means permit axial movement of said lever on said pivot element into operative position.

6. Apparatus for assembling sleeved fins on pipe in which the sleeves of the fins are partially telescoped by the application of substantially equal forces to each fin as it is telescoped over the sleeve of the preceding fin which comprises: means for supporting a pipe from one end only thereof, a carriage movable longitudinally of the pipe from the unsupported end toward its supported end, means for advancing said carriage continuously at a uniform speed, a support movable relative to said carriage in a direction parallel to the line of advance of said carriage, resilient means opposing rearward yielding of said support, a fin seating lever on said support, a pivot element on said support having its axis perpendicular to the line of advance of said carriage, said lever being mounted on said element for swinging movement and for displacement axially thereof, spring means urging said lever toward said support, said lever and carriage having an open ended slot and pin connection between said lever and carriage effective to hold said lever in operative position while said pin remains in said slot, said slot being disposed parallel to the direction of advance of said carriage and having its open end disposed for movement of said pin out of said slot upon predetermined rearward

displacement of said support relative to said carriage to provide for rearward swinging of said lever to inoperative position after the application of a predetermined force to a fin carried thereby, and cam means operable on said lever during continued advance to move said lever axially of said pivot element and to swing said lever toward operative position, said spring means being operable to move said lever axially on said pivot support to operative position in which said pin is located in said slot.

7. In tube finning apparatus, an endless chain, an arm rigidly connected to said chain to be advanced thereby, a bracket slidably connected to said arm for movement relative thereto in a direction parallel to the direction of chain advance, resilient means opposing movement of said bracket rearwardly away from said arm, a fin supporting lever on said bracket, means on said bracket mounting said lever for swinging movement rearwardly of the direction of chain advance, lock means effective to prevent rearward swinging of said lever, said lock means including portions disengageable upon predetermined rearward movement of said bracket to effect abrupt release of said lock means.

8. Structure as defined in claim 7 in which a pair of said levers are provided on said bracket, each of said levers having an arcuate fin engaging portion of substantially 180 degrees arcuate extent.

9. Pipe finning apparatus comprising a pipe support, assembly means for assembling fins having tubular sleeve portions and flat fin portions at one end of the sleeve portions onto the pipe, said assembly means comprising a first member movable longitudinally of the pipe, a second member carried by said first member and movable rearwardly therefrom, resilient means connected to said second member to oppose rearward movement thereof relative to said first member, lever means on said second member mounted for rearward swinging movement thereon in assembling fins on the pipe, said lever means including fin engaging means of arcuate shape adapted to support a fin for advance over the pipe with the finned end of the sleeve portion foremost, said fin engaging means substantially completely surrounding the sleeve portion of the fin and engaging the rear side of the fin portion thereof closely adjacent to the sleeve portion, and engageable abutment means on said lever means and said first member responsive solely to pressure developed in drawing the sleeve portion of the fin carried by said lever means over the sleeve portion of the preceding fin on the pipe to lock said lever means against any rearward swinging until a predetermined pressure has been developed by said resilient means and then to effect abrupt release of said lever means for substantially free rearward swinging movement.

10. In pipe finning apparatus, an arm adapted for forward movement longitudinally of a pipe to be finned, a bracket movable rearwardly from said arm, a plurality of guide pins interconnecting said arm and bracket, resilient means operatively engaged with said bracket to urge said bracket toward said arm, a fin supporting lever on said bracket, lock means including engageable parts on said arm and on said lever preventing rearward swinging movement of said lever while said parts are engaged, said parts being shaped to disengage upon predetermined movement of said bracket rearwardly with respect to said arm.
